UNITED STATES PATENT OFFICE

157,207

CASING FOR CIGARETTE LIGHTER, LIP-STICK, OR SIMILAR ARTICLE

Margaret Roth, New York, N. Y., assignor to Roth & Steiner, Inc., New York, N. Y., a corporation of New York

Application June 16, 1948, Serial No. 147,008

Term of patent 14 years

(Cl. D48—27)

To all whom it may concern:

Be it known that I, Margaret Roth, a citizen of the United States of America, residing in New York city, county of New York, and State of New York, have invented a new, original, and ornamental Design for a Casing for Cigarette Lighter, Lipstick or Similar Article, of which the following is a specification, reference being had to the accompanying drawing, forming part thereof, wherein,

Figure 1 is a perspective view of a casing for cigarette lighter, lipstick, or similar article showing my new design.

I claim:

The ornamental design for a casing for cigarette lighter, lipstick, or similar article, substantially as shown.

MARGARET ROTH.
